DESIGN FOR A TABLE TENNIS RACKET

Finn Magnus, East Orange, N. J.

Application December 1, 1936, Serial No. 66,232

Term of patent 14 years

To all whom it may concern:

Be it known that I, Finn Magnus, a subject of the King of England, residing at East Orange, in the county of Essex and State of New Jersey, have invented a new, original, and ornamental Design for Table Tennis Racket, of which the following is a specification, reference being had to the accompanying drawing, forming part thereof.

In said drawing Figure 1 is a front face view,

The surfacing indicated in Fig. 1 is continued over the entire faces of the blade.

I claim:—

The ornamental design for a table tennis racket, as shown and described.

FINN MAGNUS.
